CLAIM

The ornamental design for a dual device cover for an electrical junction box, as shown and described.

DESCRIPTION

FIG. 1 is a front, top perspective view of a dual device cover for an electrical junction box;

FIG. 2 is a front elevation perspective view thereof;

FIG. 3 is a rear elevation view thereof;

FIG. 4 is a top plan view thereof;

FIG. 5 is a bottom plan view thereof;

FIG. 6 is a left-side elevation view thereof; and,

FIG. 7 is a right-side elevation view thereof.

Structures shown in dash-dot broken lines form no part of the claimed design.

1 Claim, 5 Drawing Sheets
